ATTIC ACCESS DORMER VENT

Filed May 7, 1951

UNITED STATES PATENT OFFICE

2,692,548

ATTIC ACCESS DORMER VENT

Fred Knorr, Phoenix, Ariz.

Application May 7, 1951, Serial No. 224,915

5 Claims. (Cl. 98—42)

1

This invention pertains to improvements in attic access dormer vents for use in connection with roof structures of buildings.

One of the objects of this invention is to provide an improved attic access dormer vent which provides for adequate ventilation below a diagonal roof surface while at the same time providing an access opening to get into the attic area below the roof for purposes of examination, adjustment of equipment and the like.

Another object of this invention is to provide an improved combined attic ventilator and access cover arrangement which is self-contained and may be opened under adverse weather conditions such as high winds and which may be secured in place to accommodate itself to any type of severity of weather.

Still further object of this invention is to provide an attic access dormer vent for a sloping roof which is hingedly mounted to the frame structure of the vent in such a manner that it may be readily manipulated with one hand for opening and closing while providing weather protection under all conditions and a ventilating area in the vent structure for the under roof area of the building.

Further features and advantages of this invention will appear from a detailed description of the drawings in which:

Fig. 1 is an outside perspective view of the attic access dormer vent incorporating the features of this invention.

Fig. 2 is a section on the line 2—2 of Fig. 1.

Fig. 3 is an enlarged perspective view of one of the hinges.

Fig. 4 is a section on the line 4—4 of Fig. 1 showing the locking device for holding the vent in closed position.

For exemplary purposes this invention is shown applied to an attic access dormer vent customarily used in connection with slanting roof structures such as the roof 10 having the usual roofing material 11 such as slate, tile, tar paper or the like. Fixed to the sheeting boards 12 carried by the roof rafters 13 is the base frame or jack section 14 comprising the portions 15, 16, 17, and 18 appropriately secured together to form the rectangular or square frame. An upturned lip or baffle section 19 is provided around the inner opening of the frame 14 and coincides with the opening provided in the sheeting boards 12 of the roof. The frame structure 14 is securely nailed or screwed to the sheeting boards 12 in any suitable manner.

An access cover 20 is provided with a louvered

2

front face 21 having a series of louver blades 22 and a screen 23 fixed to the inside of the louvered opening. Extending backwardly from the front 21 are the side portions 24 and 25 which terminate in the top cover portion 26 to form a complete unitary structure. The top surface 26 preferably extends back substantially horizontally to engage the side portions 24 and 25 in the edge 27, which edge in turn is connected thru suitable hinges 28 and 29 to the frame member 16 of the frame 14 fixed to the roof as described. Thus the cover may be swung from the closed position 20a, Fig. 2, to the opened position 20b, Fig. 2, so that entrance may be gained through the frame 14 to the interior portion under the roof 10.

When the cover 20 is swung forward to closed position a clamping screw 27a carried in the lower of the louvers 22 is adapted to engage in an opening 29 in the strip 30 secured to the member 18 of the frame 14 fixed to the roof of the building structure. Thus in this way the cover is securely held in position on the roof against any adverse weather conditions. It is also to be noted that it folds back by means of the hinges 28 and 29 to the positions 20b, Fig. 2, so as to in no way obstruct access through the opening in the member 14 and at the same time can not be dislodged by high wind velocity when in opened position.

While the apparatus herein disclosed and described constitutes a preferred form of the invention, it is also to be understood that the apparatus is capable of mechanical alteration without departing from the spirit of the invention and that such mechanical arrangement and commercial adaptation as fall within the scope of the appendant claims are intended to be included herein.

Having thus fully set forth and described this invention, what is claimed as new and desired to be secured by United States Letters Patent is:

1. An attic access dormer vent comprising, a flat plate base frame fixed to the roof having an opening coinciding with an opening through said roof, an upturned lip formed around the edge of said opening in said base frame, a dormer vent cover comprising a vertically disposed louver opening facing down slope of the roof, a series of louvers in said vertically disposed louver opening, screen means behind said louvers fixed to said cover, a substantially horizontally disposed top surface on said cover terminating in vertically disposed side portions, and hinge means mounted on the top surface of said base frame connecting the rear edge of said top surface to

said frame so that said cover may be swung from a closed position over said frame to an open position up slope of said roof to provide an access and ventilating opening for the roof structure.

2. An attic access dormer vent comprising, a flat plate frame member fixed to the roof having an opening coinciding with an access opening in said roof of a building, an upturned lip formed around the edge of said opening in said frame member, a dormer shaped vent cover hingedly connected at its upper rear edge to the top upper surface of said frame, a vertically disposed louver opening in the down slope face of said dormer, a plurality of louvers fixed in said opening, screen means behind said louvers, said dormer shaped vent cover comprising a substantially horizontal top portion terminating in vertically disposed side portions interconnecting the rear portion of said cover with said louvered front face.

3. An attic access dormer vent comprising, a frame member fixed to the roof having an opening coinciding with an access opening in said roof of a building, an upturned lip formed around the edge of said opening in said frame member, a dormer shaped vent cover hingedly connected at its upper rear edge of the top upper surface of said frame, a vertically disposed louver opening in the down slope face of said dormer, a plurality of louvers fixed in said opening, screen means behind said louvers, said dormer shaped vent cover comprising a substantially horizontal top portion terminating in vertically disposed side portions interconnecting the rear portion of said cover with said louvered front face, and locking means interconnectable between the lower louver of said front face and said frame to secure said cover in closed position over said access opening of said frame.

4. A dormer vent closure for an access opening in a sloping roof structure comprising, a flat plate frame having a central opening mating the access opening in said roof, an upturned lip formed around the edge of said central opening in said flat plate frame, a dormer shaped cover for said opening including hinges for securing the upper rear edge of said dormer shaped cover to the top upper surface of said frame so that

said cover may be swung upwardly and backwardly on the up slope portion of the roof above said access opening, a substantially horizontally disposed top surface on said cover terminating in substantially vertically disposed side surfaces thereof, a ventilating opening in the front down slope facing surface of said dormer shaped cover, a plurality of louvers in said ventilating opening, screen means disposed behind said louvers, said upturned lip extending upwardly inside of said cover to provide a water tight weather proof structure for said roof.

5. A dormer vent closure for an access opening in a sloping roof structure comprising, a flat plate frame having a central opening aligned with the access opening in said roof, an upturned lip formed around the edge of said central opening in said frame, a dormer shaped cover for said opening including hinges for securing the upper rear edge of said dormer shaped cover to the top upper surface of said frame so that said cover may be swung upwardly and backwardly on the up slope portion of the roof above said access opening, a substantially horizontally disposed top surface on said cover terminating in substantially vertically disposed side surfaces thereof, a ventilating opening in the front down slope facing surface of said dormer shaped cover, a plurality of louvers in said ventilating opening, screen means disposed behind said louvers, said upturned lip extending upwardly inside of said cover to provide a water tight weather proof structure for said roof, and locking means interconnected between the lower louver of said louvered portion of said cover and the top surface of said frame for securing said cover in closed position on said frame.
